United States Patent Office.

EUGENE PAULUS, OF PHILADELPHIA, PENNSYLVANIA.

Design No. 3,168, dated August 25, 1868.

DESIGN FOR A TOP PLATE FOR WATCH.

The Schedule referred to in these Letters Patent and making part of the same.

TO ALL WHOM IT MAY CONCERN:

Be it known that I, EUGENE PAULUS, of the city of Philadelphia, in the county of Philadelphia, and State of Pennsylvania, have originated and designed a new Pattern for a Watch-Frame, composed of the top plate with a double-cap-jewelled bridge, and a balance-bridge, of which the following is a full, clear, and exact description, reference being had to the accompanying specimens or drawings, making part of this specification.

Figure 1 represents a top view of a watch-frame, in which are seen a new pattern for a three-fourth top-plate balance-bridge and a double-cap-jewelled bridge adapted for the staff of the pallet and escapement-wheel, and of which the shape and configuration are delineated by the red boundary lines X.

The configuration of the top plate may be generated by the ordinary circular line around the centre, and the peculiar shape, which may be defined as a straight line parallel to the diameter, intercepted by a circular curve around the winding-arbor, and an inside curve around the balance-rim, intercepted itself by a circular curve around the pallet-jewel.

The double-cap-jewelled bridge is formed by two curves around the jewels of the pallet and escapement-wheel, joined together by two lines forming a conical shape.

The balance-bridge is generated by an inside curve around the barrel, and an outside curve around the front plate, united by a double curve around the balance-rim, which curves give a long range to the regulator, and from which projects the part which holds the balance-staff as usual.

Figure 2 is an inside view of the reversed plate.

What I claim, and desire to secure by Letters Patent, is—

A new design or pattern for the top plate of a watch, the balance-bridge, and double-cap-jewelled bridge, delineated by the red boundary lines X, substantially as described and represented in the accompanying drawings.

Philadelphia, July 25, 1868.

E. PAULUS.
